UNITED STATES PATENT OFFICE

2,546,000

ELECTROMAGNETIC ACTUATOR

Ralph B. Immel, Pittsburgh, Pa., assignor to
Westinghouse Electric Corporation, East Pitts-
burgh, Pa., a corporation of Pennsylvania

Application January 10, 1948, Serial No. 1,592

6 Claims. (Cl. 175—345)

1

My invention relates to electromagnetic contactors and is especially concerned with the pivot bearing and movable contact and armature assembly of such contactors.

In contactors of conventional design, the movable structure, comprising the magnet armature and the movable contacts, is fulcrumed about a pivot bearing of fixed position relative to the stationary contactor structure. For instance, there are contactors whose movable assembly is pivoted by means of a knife-edge bearing bar which is rigidly mounted on the magnet support bracket of the contactor.

An appreciable cost item in the manufacture of such contactors is due to the fact that slight deviations of the individual parts from the correct dimensions and the accumulation of tolerances in the completed assembly may result in too little or too much contact overtravel so that the number of rejects is appreciable, and it is also infeasible to salvage all parts of contactors ejected for such deficiencies.

It is an object of my invention to greatly reduce or substantially eliminate these shortcomings of the known contactors and to make it possible that all contactors manufactured on an assembly line can be set for a desired value of overtravel.

It is also an object of the invention, relating to multi-pole contactors, to permit adjusting the different movable contacts of a contactor so that all moving contacts touch the respective stationary contacts simultaneously.

Another and subsidiary object of my invention is to achieve these results with the aid of structural means of utmost simplicity and minimum space requirements in order to secure appreciable overall savings in cost over the known contactors of otherwise comparable type and rating.

According to my invention, I provide the contactors with a knife-edge type bearing structure whose stationary bearing member, pivotally engaged by the movable contact and armature assembly, is displaceable relative to the magnet and the stationary contacts approximately in parallel to the direction of contact overtravel, and I provide fastening means for permanently securing the stationary bearing member in an adjusted position.

According to another feature of my invention, I provide the displaceable bearing structure with the stationary abutment for the armature biasing spring so that the positional relation of the spring and the magnitude and direction of its biasing force relative to the movable assembly are not

2

affected by positional changes of the bearing structure.

These and more specific objects and features of my invention will be apparent from the following description of the embodiment shown in the drawings, in which:

Figure 1 is a lateral and part-sectional view of a contactor according to the invention, while Figs. 2 to 8 show details of the same contactor; 10 more specifically

Fig. 2 is a top view of a magnet bracket;

Fig. 3 is a top view of a bearing bracket, assembled with a sectionally shown cradle structure;

15 Fig. 4 is a partial top view of the cradle structure, and Fig. 5 is a partial front view of the same structure;

Fig. 6 is a bottom view of a spring abutment member appertaining to the cradle structure;

20 Fig. 7 is a lateral view of the magnet bracket assembled with the bearing bracket, the latter being shown in an adjustment different from that illustrated in Fig. 1; and

Fig. 8 is a partial top view of the parts shown 25 in Fig. 7.

All foregoing references to top, bottom and lateral views are based on the showing of Fig. 1 which represents the contactor in the normal position in which it is to be used, the magnet being assumed to be energized and the contacts being closed in opposition to the armature bias.

According to Fig. 1, the contactor has a base plate 1 to be mounted on a panel or other support. An insulator 2 is firmly secured to the base 1 and carries stationary contacts 3 and 4. 30 A movable contact member 5 bridges the stationary contacts 3 and 4 when in the illustrated closed position. The contact member 5 is mounted in a stirrup-shaped guide member 6 which is attached to the insulating body 7 of an armature assembly. A coiled contact spring 8 disposed in the guide member 6 biases the movable contact member 5 away from the insulating body 7. The body 7 is firmly secured to a cradle 35 structure 9 of sheet metal which is pivoted for angular motion about a stationary pivot edge extending perpendicularly to the plane of illustration at the point surrounded in Fig. 1 by a broken circle denoted by 10. A magnet armature 11 is

40 pivoted to the cradle structure 9 at 12 for limited angular motion relative to the structure 9 and is biased toward center position by a leaf spring 13. The electromagnet of the contactor has a laminated frame structure 14 equipped with a coil 45 15 and fastened to the base 1 by means of

brackets 16 and 17. A bearing bracket 18 is located adjacent the bearing bracket 17. The bracket 18 is adjustable relative to the base 1 by means of adjusting screws, such as the one shown at 19 in Fig. 1, and is attached to the magnet bracket 17 by fastening screws 20 and 20' (Figs. 1 to 3, 7, 8). The foot portion 21 of the bearing bracket 18 adjacent to the base 1 is provided with an abutment 22 for an armature biasing or kick-out spring 23 whose other end engages an abutment 24 associated with the cradle structure 9 of the armature assembly.

According to Fig. 2, the magnet bracket 17 has two elongated openings 25 and 25' for the passage of the respective fastening screws 20 and 20'. Two lugs 26 and 26' of the magnet bracket 17 have threaded bores for receiving respective screws 27 and 27' which fasten the magnet frame 14 to the bracket (Figs. 1, 2).

The bearing bracket 18, according to Fig. 3, has threaded bores for receiving the fastening screws 20 and 20'. Due to the elongated shape of openings 25 and 25' in bracket 17, the bearing bracket 18 can be displaced to a limited extent in the horizontal direction relative to the showing of Fig. 1. The bearing bracket 18 has a middle portion 28 (Fig. 3) and two lateral arms 29 and 29' so as to have the general shape of the letter T. The arm 29 of the T-shaped bracket portion is provided with the above-mentioned pivot edge 10 which is interrupted by a projecting lug 30 (Fig. 3). The arm 29' has a corresponding pivot edge 10' and a projecting lug 30'. The two edges 10 and 10' are in alignment with each other.

The cradle structure 9 appertaining to the movable armature assembly forms abutments 31 and 32 (Figs. 1, 4, 5) for holding the armature centering spring 13 (Fig. 1) in proper position and is also equipped with two small flanges 33, 33' and two large flanges 34 and 34' (Figs. 1, 3, 4, 5). The part of the cradle structure having the large flanges 34, 34' straddles the bracket 17 as well as the bearing bracket 18. The flange 34' has an opening 35' engaged by the lug 30' of the bearing bracket 18 (Figs. 3, 5). The flange 34 (Fig. 1) has a corresponding opening 35 engaged by the lug 30 (Fig. 3). The flanges 34 and 34' are further provided with a threaded opening at 36 or 36' (Figs. 1, 5) for receiving respective fastening screws that secure the insulating body 7 to the cradle structure 9 of the armature assembly. One of these screws is indicated in Fig. 1 and denoted by 37. The flange 34' as shown in Fig. 5 has a cut-out notch at 38' and the flange 34 has a corresponding notch (not shown). These two notches receive the ends of a separate abutment member 39 (Fig. 6) which is provided with the above-mentioned abutment 24 for the kick-out spring 23 (Figs. 1, 6). The spring 23 holds the abutment member 39 in engagement with the cradle structure 9. It also biases the cradle structure into proper engagement with the pivot edges 10 and 10' and biases the armature assembly toward the contact opening position.

The bearing bracket 18 has a projection 42 (Figs. 1, 7, 8) which serves as a spacing element and abuts against the bracket 17. The foot portion 21 of the bearing bracket 18 has a button-hole opening 43 and a marginal opening 44 (Fig. 8). The adjusting screw 19 has a shoulder portion of reduced diameter bordered by a head 45 (Figs. 1, 7, 8). The reduced portion of the screw passes through the opening 43 while the screw thread engages a threaded bore of the base 1

and is fastened in properly adjusted position by means of a locking nut 46 (Figs. 1, 7). A second fastening screw similar to the one denoted by 19 has a reduced diameter portion which engages the marginal opening 44 and is bordered by a head 45'. The second screw is also threaded through the base 1 and secured in properly adjusted position by means of a locking nut similar to the one denoted by 46.

Referring to the illustration of Fig. 1, it will be recognized that the armature assembly, as a whole, is limited to angular movement between two positions about the geometric axis of the pivot edges. When the magnet coil 15 is de-energized, the armature assembly, under the biasing force of spring 23, is turned clockwise away from the illustrated position so that the movable contact member 5 is separated from the stationary contacts 3 and 4 and is forced against the bottom of the contact guide 6 by the contact spring 8. When the magnet coil 15 is energized, the armature 11 is attracted by the magnet and moves the assembly into the illustrated position. Near the end of that movement, the contact member 5 engages the stationary contacts and is arrested while the rest of the armature assembly is permitted to perform an additional movement (overtravel). The amount of overtravel is indicated in Fig. 1 by the distance O between two arrowheads.

When the contactor is properly adjusted, the pivot point located at 10 in Fig. 1 is substantially in alignment with the contact surfaces and with the mutually engaging surfaces of magnet and armature. It will be recognized that this proper alignment or any departure therefrom that may be necessary to obtain a desired amount of overtravel can be achieved by displacing the bearing bracket 18 relative to the magnet bracket 17 and then fastening it in the correct position.

When assembling the contactor, the magnet brackets 16, 17 and the insulator 2 with the stationary contacts 3 and 4 are first secured to the base 1. Then the two fastening screws 19 are threaded into the base plate 1. The bearing bracket 18 is then placed on the screws 19 by passing it over the reduced portions of the screws by means of the button-hole 43 and the marginal opening 44 (Figs. 7, 8). The bracket 18 is then moved toward the right relative to Fig. 8 in order to engage it with the shouldered ends of the screws. Next, the locking screws 20 and 20' are screwed through the openings 25 and 25' (Fig. 2) into the bearing bracket. To adjust the overtravel of the armature assembly to the proper value, the armature assembly may be held in its closed position as shown in Fig. 1. Then the two adjusting screws 19 are turned with a screwdriver from the rear of base 1 until the overtravel is correct. Then the adjusting screws are securely locked in place by the lock nuts 46. Thereafter, the bearing bracket 18 is securely clamped to the magnet bracket 17 by tightening the screws 20 and 20'. Due to the fact that two adjusting screws are used, the bearing bracket can readily be set so that all moving contacts of a multi-pole contactor touch the stationary contacts simultaneously. By virtue of the fact that the armature biasing spring 23 has its stationary abutment located at the foot portion 21 of the bearing bracket 18, the proper alignment and positioning of the spring is not affected by the just-mentioned adjustment of the bracket. The armature assembly is thus made self-aligning on its support and the dis-

placement of the pivot edges does not disturb the proper adjustment and performance of the magnetic and contact devices.

It will be obvious to those skilled in the art that the details of contactors according to my invention can be modified in various respects without departing from the essential features of the invention set forth in the claims annexed hereto.

I claim as my invention:

1. In a contactor, the combination of a base having a front surface, an electromagnet, a fastening bracket rigidly connecting said magnet to said base and having a bracket portion extending at a substantially right angle away from said base surface, a bearing structure having a spring abutment near said base surface and having a portion facing said bracket portion, said bearing structure having a pivot edge parallel to and spaced from said base surface and facing said surface, an assembly having a rigid portion engaging said edge to be angularly movable between two positions about said edge, a compression spring engaging said assembly and said spring abutment for biasing said assembly toward said edge and toward one of said positions, said assembly having an armature adjacent said magnet for moving said assembly to said other position under control by said magnet, said bearing structure being displaceable along said bracket portion toward and away from said base, and fastening means for rigidly securing said bearing structure in a selected position.

2. In a contactor, the combination of a base, an electromagnet, fastening means rigidly connecting said magnet to said base and having a bracket secured to said base and extending at a substantially right angle away from said base, a bearing structure having a spring abutment near said base and having a portion in face-to-face engagement with said bracket, said bearing structure having a pivot edge remote from said base and facing said base, an assembly having a rigid structure disposed between said base and said edge and engaging said edge so as to be angularly movable between two positions about said edge, a compression spring engaging said structure and said spring abutment for biasing said assembly toward said edge and toward one of said positions, said assembly having an armature adjacent said magnet for moving said assembly to said other position under control by said magnet, said bearing structure being displaceable along its engaging surface with said bracket toward and away from said base, and fastening screw means traversing said bearing structure and said bracket for firmly securing said structure in an adjusted position and being operatively accessible at a place away from said spring.

3. In a contactor, the combination of a base, bracket means firmly secured to said base and having a bracket extending at a substantially right angle away from said base, an electromagnet attached to said bracket means in spaced relation to said base and disposed at one side of said bracket, an angular bearing structure disposed at the other side of said bracket and having a substantially T-shaped portion adjacent to and facing said bracket and having a foot portion

extending away from said bracket and facing said base, said T-shaped portion of said structure having two arms extending laterally beyond said bracket and having mutually aligned pivot edges facing said base, said edges being spaced from and parallel to said base, a pivotally movable rigid cradle, an armature attached to said cradle near said magnet at said one side of said bracket, said cradle having a bifurcated part straddling

5 said bracket as well as said bearing structure at a place between said base and said arms and being in pivotal engagement with said pivot edges, said assembly having an abutment member extending across said bifurcated part at said other 10 side of said bracket, and a compression spring 15 abutting against said foot portion of said bearing structure and against said abutment member of said assembly for biasing said assembly toward said edges and to a pivotal position away from 20 said magnet.

4. In a contactor according to claim 3, said abutment member being separable from said bifurcated part of said assembly, said part having a notch means for receiving said abutment member, and said spring being slanted from said foot 25 portion toward said abutment member so as to bias said abutment member into said notch means thus securing said abutment member to said bifurcated part.

5. In a contactor according to claim 3, said T-shaped portion of said bearing structure being in face-to-face contact with said bracket only at a place near said base but being spaced away from said bracket near said arms and edges, 30 said structure having a spacing element located near said arms and abutting against said bracket.

6. In a contactor according to claim 3, said T-shaped portion of said bearing structure being in face-to-face contact with said bracket only 35 at a place near said base but being spaced away from said bracket near said arms and edges, said bearing structure being displaceable along said bracket in a direction toward and away from said base, said bracket having two holes elongated in 40 said direction and spaced from each other across said direction so as to lie on both sides respectively of said spring, and two screws operatively accessible from one side of said bracket and engaging said bearing structure through said respective holes for fastening said bearing structure in an adjusted position.
